CLAIM

The ornamental design for a display screen of an infusion device with graphical user interface, as shown and described.

DESCRIPTION

The sole FIGURE is a front view of a display screen or portion thereof of an infusion device with graphical user interface, showing the new design.

The outermost broken-line rectangle illustrates the perimeter of a display screen or portion thereof. The remaining broken lines illustrate portions of a graphical user interface. The broken lines form no part of the claimed design.

1 Claim, 1 Drawing Sheet
